UNITED STATES PATENT OFFICE.

ROBERT F. HALL, OF SCHENECTADY, NEW YORK.

LOCOMOTIVE.

Application filed February 21, 1923. Serial No. 620,428.

To all whom it may concern:

Be it known that I, ROBERT F. HALL, a citizen of the United States, and a resident of Schenectady, in the county of Schenectady and State of New York, have invented a certain new and useful Improvement in Locomotives, of which improvement the following is a specification.

My invention relates, generally, to locomotive engines of the type on which, through the intermediation of a cranked driving axle, more than two main or operating steam cylinders are installed, their pistons acting to effect the rotation of the main driving wheels, as in those known as three-cylinder engines, and, particularly, to the species of that type set forth in an application for Letters Patent of the United States, filed by me January 13, 1923, Ser. No. 612,406, now Patent No. 1,464,931, granted Aug. 14, 1923. In the locomotive disclosed in said application, the centre cylinder is of less capacity than the outside cylinders.

The object of my present invention is to enable the irregularity introduced in the turning moment by the inequality of cylinder capacities to be substantially minimized in practical service.

The improvement claimed is hereinafter fully set forth.

In the accompanying drawings: Figure 1 is a diagrammatic side view of so much of a three-cylinder locomotive engine as illustrates an application of my invention; Fig. 2, a plan view of the same; Fig. 3, a front view, in elevation; Fig. 4, a diagram showing the ideal equal angular relation of the three cranks of a three-cylinder locomotive; Fig. 5, a diagram of similar character, showing the two outside cranks as 110 degrees apart, and the angle between the centre crank and each of the side cranks as 125 degrees; Fig. 6, an ideal turning moment diagram for a three-cylinder engine, all the cylinders of which are of equal capacity, and with the cranks in the angular relation shown in Fig. 4; Fig. 7, a similar diagram for a three-cylinder engine, the centre cylinder of which is of less capacity than the outside cylinders, and with all cranks 120 degrees apart, as in Fig. 4; and, Fig. 8, an ideal turning moment diagram of a three-cylinder engine, having the centre cylinder of less capacity than either of the two outside cylinders, and with the two outside cranks 110 degrees apart, as in Fig. 5.

One of the principal advantages of the three-cylinder type of locomotive, is its uniform turning moment, as compared with that of the two-cylinder type, and the lesser fluctuations of this turning moment, above and below its mean value. As the force delivered at the circumference of the driving wheels, which moves the engine relatively to the track (commonly termed the "tractive force") varies directly as the turning moment, the value of the maximum turning moment, for a given design, determines the limit of the cylinder power which can be provided, relatively to the weight on the driving wheels, or "adhesive weight". It consequently follows that in the three-cylinder engine, in which the fluctuations of turning moment and tractive force, above their mean values, is less than in the two-cylinder type, the mean cylinder power can be greater, with respect to the weight on the driving wheels, than in the two-cylinder type. By reference to Fig. 6, which is a turning moment diagram for three cylinders, of equal capacity, and cranks 120 degrees apart, the even character of the turning moment will be apparent. The shape of the curve is influenced by the net pressure acting on the piston at any particular crank position, by the relation of length of main rod to the length of crank (or the "angularity" of main rod), by the relation of the longitudinal axes of the cylinders to a horizontal plane through the centres of the driving axles, and also by the angular relation of the cranks to each other. The inertia of the moving parts also operates to change the character of the diagram, but as this tends to correct the unevenness, and also as its effect at low velocities is small, it was not considered in preparing the diagrams shown in Figs. 6, 7 and 8. The effect of the angularity of the main rods renders the diagram unsymmetrical, and for the sake of more clearly illustrating the principles involved, the main rod has been considered as of infinite length. The turning moment diagrams shown in Figs. 6, 7 and 8, differ somewhat from those which form a part of the previous application, in that a different relation of cylinder capacity is used, and the net pressure urging the piston forward at the different points of the stroke are also different. At the lower part of each diagram is shown the separate turning-moment phases of each

cylinder together with the angular relation between these phases, while the top line is the sum of the turning moments of all three phases at all angular positions of the 5 crank, through a complete revolution, or 360 degrees. In Figs. 6, 7 and 8, phases 5, 5^a, and 5^b, 8, 8^a and 8^b, are for the centre cylinder, while phases 4, 4^a and 4^b, 6, 6^a and 6^b, 7, 7^a and 7^b, 9, 9^a and 9^b, are for the two 10 outside cylinders.

My invention is herein exemplified as applied in a three-cylinder single-expansion locomotive having a central cylinder, 1, and two side cylinders, 1^a 1^b. The pistons of all 15 the cylinders are, as in ordinary practice, coupled, by main connecting rods, 1^f, to crank pins, fixed in a crank, 9^a, and crank arms on driving wheels, 9^c, on a main driving axle, 9. Steam is supplied from the 20 boiler, 11^c, to the distribution valve chests, 2^c, of the cylinders, through which it is admitted to, and exhausted from, the cylinders, by the distribution valves, in the ordinary manner. Various forms of valve gear, 25 by which the distribution valves may be operated, to effect the cut-off desired, are well known in standard practice, and not, in and of themselves, forming part of my present invention, are not herein exemplified.

30 In order to eliminate, or reduce to the lowest degree practicable, the lack of uniformity in turning moment, in a three-cylinder engine, the centre cylinder of which is of less capacity than the outer cylinders, 35 which will be indicated by a comparison of the diagrams, Figs. 6, 7 and 8, as presently to be explained, the outer crank arm pins are, under my invention, as indicated in Fig. 5, disposed at an angle which is less 40 than one-third of the circumference of their stroke, as, say, one of 110 degrees, and at equal angles, as, say, 125 degrees, to the crank pin of the centre cylinder.

Referring to the diagrams, Fig. 7 is a 45 turning moment diagram of a three-cylinder engine of approximately equal power to that of which a turning moment diagram is shown in Fig. 6. In this diagram, however, the centre cylinder is less in capacity than 50 the two outside cylinders, but all cranks are 120 degrees apart as in Fig. 6. Fig. 8 is a turning-moment diagram of the same cylinders as those in Fig. 7, but with the two outside cranks 110 degrees apart instead of 55 120. It will be noted in Fig. 7 that phases 11^a and 14^a of the combined turning-moment diagram are lower, and that phases 10^a, 12^a, 13^a, and 15^a, are higher in relation to the mean 60 turning-moment line 16^a—16^a than the corresponding phases 11 and 14, and 10, 12, 13 and 15 are to line 16—16 in Fig. 6. The effect of bringing the outside cranks closer

together is shown in Fig. 8 and consists in 65 in bringing the turning moment phases 4^b and 6^b, and 7^b and 9^b closer to each other than 4^a and 6^a, and 7^a and 9^a in Fig. 7, with the result that phases 11^b and 14^b are higher, 70 while phases 10^b, 12^b, 13^b and 15^b are lower than the corresponding phases in Fig. 7. This results in a more even turning moment 75 and one which has a less fluctuation above and below its mean value than that shown in Fig. 7.

While Fig. 5 shows 110 degrees between the two outside cranks and an equal angular 80 spacing of 125 degrees between the centre crank and the two outside cranks, these relations may be varied without departing from the spirit of my invention. For example, with some conditions of main rod 85 length, etc., it may be found desirable to make the angle between the two outside cranks either less than 110 degrees, or more than 110 degrees, but less than 120 degrees; and for constructional reasons in locating the 90 centre cylinder, the angles between the centre crank and the two outside cranks may either be made equal, as shown in Fig. 5, or unequal.

I claim as my invention and desire to secure by Letters Patent:

1. In a single-expansion locomotive, the combination of a cranked driving axle; end crank arms, fixed thereon, at an angle less than 120 degrees; a central cylinder and two 95 outside cylinders, the capacity of the central cylinder being less than that of either of the two outside cylinders; and connections, coupling the pistons of said cylinders to the crank arms of the driving axle. 100

2. In a single-expansion locomotive, the combination of a cranked driving axle; end crank arms fixed thereon, at an angle less than 120 degrees and at unequal angles to the crank of the driving axle; a central cylinder and two outside cylinders, the capacity of the central cylinder being less than that of either of the two outside cylinders; and connections, coupling the pistons of said cylinders to the crank arms of the 110 driving axle. 105

3. In a single-expansion locomotive, the combination of a cranked driving axle; end crank arms fixed thereon, at an angle of substantially 110 degrees; a central cylinder and two outside cylinders, the capacity of the central cylinder being less than that of either of the two outside cylinders; and connections, coupling the pistons of said cylinders to the crank arms of the driving axle. 115

ROBERT F. HALL.
